(57) **CLAIM**

The ornamental design for a container carrier, as shown and described.

DESCRIPTION

FIG. 1 is a front perspective view of a container carrier, showing a first embodiment of our new design in a folded configuration;

FIG. 2 is a front elevational view of FIG. 1, the rear elevational view being a mirror image thereof;

FIG. 3 is a left-side elevational view of FIG. 1, the right-side elevational view being a mirror image thereof;

FIG. 4 is a top plan view of FIG. 1;

FIG. 5 is a bottom plan view of FIG. 1;

FIG. 6 is a top plan view thereof, illustrated in a flat configuration;

FIG. 7 is a front perspective view of a second embodiment thereof, illustrated in a folded configuration;

FIG. 8 is a front elevational view of FIG. 7, the rear elevational view being a mirror image thereof;

FIG. 9 is a left-side elevational view of FIG. 7, the right-side elevational view being a mirror image thereof;

FIG. 10 is a top plan view of FIG. 7;

FIG. 11 is a bottom plan view of FIG. 7; and,

FIG. 12 is a top plan view thereof, illustrated in a flat configuration.

The broken lines shown in the drawings are for the purpose of illustrating parts of the article and exemplary cans that form no part of the claimed design. The dot-dash style

(Continued)

broken lines shown in the drawings represent a boundary and form no part of the claimed design.
